UNITED STATES PATENT OFFICE

137,626

DESIGN FOR A LINEN TRUCK

Wilbur Henry Adams, Erie, Pa., assignor to The Colson Corporation, Elyria, Ohio, a corporation of Ohio

Application November 9, 1943, Serial No. 111,635

Term of patent 7 years

(Cl. D14—3)

To all whom it may concern:

Be it known that I, Wilbur Henry Adams, a citizen of the United States, residing at Erie, in the county of Erie and State of Pennsylvania, have invented a new, original, and ornamental Design for Linen Truck, of which the following is a specification, reference being had to the accompanying drawings, forming a part thereof.

The characteristic features of my design are shown in full lines in the drawings.

I claim:

The ornamental design for a linen truck, substantially as shown and described.

WILBUR HENRY ADAMS.
